C. W. BECK.

CONNECTOR FOR ELECTRICAL CONDUCTORS.

APPLICATION FILED MAR. 12, 1908.

Patented Dec. 8, 1908.

UNITED STATES PATENT OFFICE.

CHARLES W. BECK, OF ROCKVILLE CENTER, NEW YORK.

CONNECTOR FOR ELECTRICAL CONDUCTORS.

No. 906,370.

Specification of Letters Patent.

Patented Dec. 8, 1908.

Application filed March 12, 1908. Serial No. 420,563.

To all whom it may concern:

Be it known that I, CHARLES W. BECK, a citizen of the United States, residing at Rockville Center, county of Nassau, State of

5 New York, have invented certain new and useful Improvements in Connectors for Electrical Conductors, of which the following is a specification, reference being had thereto in the accompanying drawings, in

10 which—

Figure 1 is a plan view of the device applied to a binding post, said post being shown in transverse section; Fig. 2 a horizontal sectional view thereof showing the connector open to receive a binding post; Fig. 3 a side elevation of the device looking in the direction of the arrow *a* in Fig. 1; Fig. 4 a vertical central longitudinal sectional view of the device; Fig. 5 a transverse sectional view on the line V—V of Fig. 1; Fig. 6 a plan view of the modified form of the connector; and Fig. 7 a side elevation thereof looking in the direction of the arrow *b* in Fig. 6.

25 This invention relates to new and useful improvements in devices for connecting conductor wires to binding posts. In the ordinary construction of the devices now generally used, the conductor wire is either directly connected to the binding post or a perforated piece is secured to the conductor wire and is adapted to receive the binding post, a binding nut being used in either case to insure a proper electrical connection.

35 Such a connection is difficult to make, many times, by reason of the difficulty of securing the binding nut on the binding post or of connecting the conductor wire to the post. Binding nuts work loose and often are 40 shaken off the binding post. This form of connection is also objectionable in that the conductor wire is rigidly connected to the binding post and any movement of the free portion of the wire tends to break it near the binding post or to detach it from the 45 perforated end piece connected to it. The perforated end piece is usually made of sheet metal and is frequently broken because of its rigid connection to the binding post.

50 One of the main objects of this invention is to provide a connector which may be readily applied to a binding post or other conductor; and which, when in position thereon, will have ample contact therewith, 55 while at the same time being free to swing around said post, or other conductor, to per-

mit the flexible conductor to be extended in any desired direction without causing any undue strain on the connection between the flexible conductor and the binding post. 60

Another object of the invention is to form the connector of a plurality of separable parts which are normally held together to form a metal clamp to receive the binding post, but which may be readily separated to 65 permit of the device being removed from the post or other conductor.

Another object of the invention is to so construct the device that when it is applied to the binding post it will engage the threads 70 thereof and prevent accidental displacement of it.

Referring to the various parts by numerals, 1 designates the main member of the connector which is provided at one end with 75 a socket 2 by which it is connected to the conductor wire. The main member is formed with the two parallel walls 3 and the connecting wall 4 which is perpendicular to the parallel walls, the three walls forming the 80 gripping member, substantially U-shape in cross section, as shown clearly in Fig. 5 of the drawings. The parallel walls are cut out at corresponding points to form the recesses 5, the wall 6 of which forms a hook. 85 The parallel walls 3 of this main member are of sufficient width to permit the binding post 7 to be received within the recess 5, as shown clearly in Fig. 1 of the drawings, and the said parallel walls are cut away sufficiently to permit the binding post to rest 90 against the wall 4 of said main member, in order to insure a good electrical contact between the binding post and the said main member. The purpose of shaping the walls 95 6 to form a hook, and of making the walls 3 broader than the diameter of the binding post, is to take up any longitudinal strain brought on the connector and to prevent any tendency of such strain opening the connector, as will be more fully hereinafter described. The main member is preferably stamped from sheet metal, but, of course, it may be made in any suitable manner.

The swinging member of the connector 105 also consists of two parallel walls 8 and a perpendicular connecting wall 9 extending along the longitudinal edges of said parallel walls, the said member being substantially U-shape in cross section as shown clearly in Fig. 110 5. The swinging member is adapted to fit closely within the main member, the two

open longitudinal edges of said member being opposed, as shown clearly in Fig. 3, so that when the swinging member is inclosed within the main member the free edges of its parallel walls will engage the perpendicular wall 4 of said main member. The parallel walls of the swinging member are cut out at corresponding points to form the recesses 8^a to receive the binding post, as shown clearly in Fig. 1, said recesses being extended back to the perpendicular wall 9 to permit said perpendicular wall to contact with the binding post.

The two members are pivoted together at their outer ends, that is, at the ends opposite the socket 2 of the main member, by a pivot pin 10, which passes through the parallel walls of said members, the swinging member being arranged to fit closely between the parallel walls of the main member. Surrounding the pivot pin is a coil spring 11, one end of which, 12, bears against the outer edge of the wall 4 of the main member of the connector, the other end 13, of the spring bearing against the outer edge of the wall 9 of the swinging member, so that the tension of the spring will hold the two members in their closed position, that is the swinging member within the main member. To release the device from the binding post, or to open it to receive the said post, the swinging member is moved outwardly against the tension of the spring 11. When the swinging member is released the spring moves it to its closed position within the main member and in contact with the binding post. The edges of the recesses in the walls 3 and 8 engage in the threads of the binding post, as shown in Fig. 4, to prevent the detachment of the device from the binding post without moving the swinging member outwardly. By this means the connector is securely attached to the binding post and may be moved around it to adjust itself to the position of the connector, while at the same time being permanently attached thereto and secure against accidental disconnection.

The swinging member is provided near its free end with a finger piece 14 which is adapted to fit within the recess 15 formed in one of the parallel walls of the main member when the said swinging member is in its closed position. By means of this finger piece the swinging member may be readily moved outwardly against the tension of the spring 11.

The conductor 16 may be secured within the socket 2 in any suitable manner, preferably by clamping the said socket around the conductor.

To lock the two members of the connector together a spring lip 15^a is formed on the main member and an interlocking lip 15^b is formed on the swinging member, these two parts interlocking as shown in Fig. 3 when

the two parts are together. When it is desired to separate the two parts a sufficient pressure on the finger piece will spring the locking lip from under the lip 15^a and permit the two parts to be swung open against the tension of the spring.

In Figs. 6 and 7 a slightly modified form of the device is shown. It consists of two semi-circular members 17 and 18 pivoted together at 19 and provided with a spring 20 for yieldingly holding the said two members together. The inner walls of these members are threaded as shown at 21 to engage the threads of the binding post; and the main member 17 is formed with a socket 22 to receive the conductor 23. On the swinging member 18 a finger piece 24 is formed by which the said member may be moved outwardly against the tension of the spring 20. These members are substantially U-shape in transverse section, being formed with parallel walls 25 and a connecting wall 26. It will be readily seen that the member 18 may be swung outwardly to permit the device to be placed over a threaded binding post, and when released the post will be grasped between the said two members.

Having thus described my invention, what I claim as new and desire to secure by Letters Patent, is:—

1. A connector for electrical conductors comprising two members pivotally connected together at their outer ends and provided with registering recesses adapted to receive a binding post, means for connecting a conductor to the inner end of one of said members, the inner end of the other member being arranged to swing outwardly from the conductor-carrying member, and means at the pivotal ends of the members to yieldingly force the two inner ends of the members towards each other whereby a lateral or sidewise strain on either of said members will tend to force them into closer contact.

2. A connector for electrical conductors comprising two members pivotally connected together at their outer ends and provided with registering recesses to receive a binding post, one of said members being provided with a conductor-receiving socket at its inner end, and the binding post-receiving recesses being formed between the pivot and said socket.

3. An electrical connector adapted to connect a conductor to a binding post comprising two members pivotally connected together and provided with recesses to receive the binding post, a spring for normally holding said two members together and in contact with the binding post and a socket formed on the end of one of said members on the opposite side of the post receiving recesses from the pivot of the two members.

4. An electrical connector comprising a pair of members U-shaped in cross-section

and adapted to fit one within the other and formed with registering recesses adapted to receive a binding post, means for pivotally connecting said members together at their 5 outer ends, whereby the inner ends may be swung outwardly away from each other to release the binding post, a spring secured to the outer ends of said members to normally hold them one within the other, and a socket 10 formed on the forward end of one member, whereby the pivot connecting the two members will be at one side of the binding post, and the socket to receive the conductor will be at the opposite side of said post.

15 5. An electrical connector comprising a pair of substantially U-shaped members, one of which is adapted to fit within the other, said members being formed with recesses extending inwardly from the free edges of 20 their parallel walls and adapted to receive a binding post, means for pivotally connecting said members together near their outer ends, a spring for yieldingly holding said members one within the other, and means for 25 connecting one of said members to a conductor, said means being on the opposite side of the binding post-receiving recesses from the pivot.

6. An electrical connector comprising two 30 members substantially U-shaped in cross-section and adapted to fit one within the other, said members being formed with registering recesses extending inwardly from the longitudinal edges of the substantially 35 parallel walls of said members, said recesses being adapted to receive a binding post and the walls of the said members around the recesses being adapted to engage the threads on the binding post, a pivot connecting together the outer ends of said members, said 40 pivot passing through the recessed parallel walls, whereby the inner ends of said members may be separated by swinging said members outwardly, a spring yieldingly 45 holding the two members one within the other, and a socket to receive a conductor formed on the outer end of one of said members and on the opposite side of the regis-

tering recesses from the pivot of said members.

7. An electrical connector adapted to connect a conductor to a binding post comprising two members U-shape in cross section and adapted to fit one within the other, the free edges of the inner member being arranged to lie close to the closed end of the outer member, the overlapping parallel walls of said members being formed with registering recesses to receive a binding post, the edges of said walls being adapted to engage 60 the threads of said binding post, a pivot extending through the overlapped walls of said members, a spring to yieldingly hold said two members in their interlocked position, a socket on the end of the main or outer 65 member to receive the conductor, said socket being on the opposite side of the post-receiving recess from the pivot.

8. An electrical connector adapted to connect a conductor to a binding post comprising two members U-shape in cross-section and adapted to fit one within the other, the free edges of the inner member being arranged to lie close to the closed end of the outer member, the overlapping parallel walls 75 of said members being formed with registering recesses to receive a binding post, the edges of said walls being adapted to engage the threads of said binding post, a pivot extending through the overlapped walls of the 80 said members, a spring to yieldingly hold said two members in their interlocked position, a socket on the end of the main or outer member to receive the conductor, said socket being on the opposite side of the post-receiving 85 recesses from the pivot, a finger piece formed on the inner member near the free end thereof and adapted to lie in a recess in the outer member.

In testimony whereof I hereunto affix my 90 signature in the presence of two witnesses this 10th day of March 1908.

CHARLES W. BECK.
